Term of patent 14 years

Int. Cl. D24—02; D9—04

U.S. Cl. D83—1

FIGURE 1 is a medical diagnostic test kit or similar article showing my new design;

FIGURE 2 is an exploded perspective view thereof with portions fragmentarily shown in section;

FIGURE 3 is an end elevation looking in the direction of line 3-3 of FIGURE 1;

FIGURE 4 is a vertical cross-section taken on line 4-4 of FIGURE 2;

FIGURE 5 is a vertical cross-section thereof taken on lines 5-5 of FIGURE 1;

FIGURE 6 is a vertical cross-section thereon taken on line 6-6 of FIGURE 1;

FIGURE 7 is a top plan view thereof with the transparent sleeve omitted;

FIGURE 8 is a side elevation thereof with the transparent sleeve omitted;

FIGURE 9 is horizontal cross-section thereof with the transparent sleeve omitted taken along lines 9-9 of FIGURE 7;

FIGURE 10 is a cross-section thereof similar to that of FIGURE 9 but taken along lines 10-10 of FIGURE 7;

This application is a continuation-in-part of my pending application Ser. No. D. 7,303, filed May 29, 1967, now abandoned.

I claim:

The ornamental design for a medical diagnostic test kit or similar article, as shown and described.
